BREAD DOUGH TRAY

Hugh H. Bridgford, 6600 Blvd. E.,
West New York, N.J. 07093

Filed Nov. 12, 1968, Ser. No. 14,415

Term of patent 14 years

Int. Cl. D9—99

U.S. Cl. D9—189

I claim:

The ornamental design for a bread dough tray, as shown.
